UNITED STATES PATENT OFFICE

2,662,353

MAGNETIC ABRASION TOOL

Harry Bergman and Otto Behnke, Chicago, Ill.

Application December 17, 1952, Serial No. 326,508

8 Claims. (Cl. 51—187)

1

Our invention relates to a magnetic abrasion tool that has reference to a tool to which a strip of abrasive material such as sandpaper or the like can be easily and quickly applied and removed from the tool quickly and easily when the abrasive paper has been worn to a smoothness that necessitates its replacement.

Another and further object of our invention is the provision of a magnetic abrasive tool in which the abrasive paper is held firmly in position while being used for sanding purposes and in which, when it is desired to change the character of the abrasive material, this change can be easily and quickly made by the workman without the use of tools or the like in order to make such change of material.

Another and further object of our invention is the provision of an abrasive tool and in which the abrasive material is placed upon a holding member in such position that it can be used in right-angled corner surfaces and abrasive action secured both on the face of the material and on the edges of the holding member, so that whatever material is removed can be done equally from both right-angled surfaces and a substantially smooth surface produced on pieces of material occupying a right angle to each other.

Another and further object of our invention is the provision of an abrasive tool which, while primarily adapted to be used with an abrasive material such as a strip of sandpaper or the like, can have a polishing material applied to the face thereof and the device can be used for polishing purposes with equal facility as it may be used with an abrasive material. These and other objects of our invention will be more fully and better understood by reference to the accompanying drawings, in which—

Fig. 1 is a horizontal plan sectional view taken on lines 1—1 of Fig. 2;

Fig. 2 is a longitudinal sectional view taken on lines 2—2 of Fig. 1; and

Fig. 3 is a transverse sectional view taken on lines 3—3 of Fig. 1.

Referring now specifically to the drawings, in which like reference characters refer to like parts throughout, a non-metallic base member 10 is shown which is substantially rectangular in shape and which has concave ends 11 and 12, also concave sides 13 and 14, to permit the fingers of the operator to grasp the base member 10 firmly in one of his hands for rubbing operation during the use of the tool. The top portion of the member 10 has curved extensions 15 and 16 extending along the sides of the member 10 while similar extensions 17 and 18 are formed along the ends of the member 10 to allow the operator to obtain a somewhat firmer grip upon the base member 10 than might otherwise be possible, so that the device will not slip out of the opera-

2

tor's hand. The base member 10 has a flat bottom 19 with extensions 20 and 21 along the sides of the base member 10, with similar portions 22 and 23 extending along the ends of the member 10 whereby the face 19 of the plate 10 is slightly larger in area than is the top of the base member 10.

A pair of recesses 24 and 25 are formed in the bottom face 19 of the member 10 and extend longitudinally of the base member 10, partially of its length. The recesses 24 and 25 are open at the bottom 19 of the base member 10 and have magnets 26, 26 mounted therein and firmly fixed into the base member 10 by being cemented therein or secured thereto in any other approved manner. A pair of bores 27 and 28 extend from the face of the plate 19 inwardly therefrom—these bores being spaced between the recesses 24 and 25 for purposes hereinafter described. A metallic plate 29 is provided of substantially the same area as the bottom face 19 of the base member 10, with dowel pins 30 and 31 being mounted in the said plate 29 and swedged into fixed relation with the plate 29 so that they are not easily removed from this plate 29, and which when the plate 29 is in position on the face 19 of the base member 10 the dowel pins 30 and 31 extend into the bores 27 and 28 so as to hold the plate 29 against a torsional or twisting displacement of the plate 29 upon the face 19 of the base member 10. A strip of cushioning material 32, such as felt, rubber, or the like, is cemented to the face of the metal plate 29 opposite to the one from which the dowel pins 30 and 31 extend to provide a cushion for a strip of abrasive material 33 which, when the device is in use, is folded around the cushioning material 32, the plate 29 with the side edges 34, 34 of the material 33 being interposed between the face 19 of the base member 10 and the plate 29, while the ends 35 of the abrasive material are folded over the ends of the plate 29 in the same manner and are gripped between the metallic plate 29 and the face 19 of the base member 10 with the magnets 26, 26 exerting a sufficient pulling force upon the metallic plate 29 to cause a firm gripping of the edge of the abrasive between the surface 19 of the base member 10 and the metallic plate 10, so that the abrasive material is held in firm engagement in position upon the tool and cannot easily be displaced therefrom, particularly during the normal use of the device.

The ends and sides of the base plate 29 are in register with the ends and sides of the cushioning material 32 so that the abrasive material 33 extends at right angles to the bottom portion thereof and is supported by the edges of the plate 29 and the edges of the cushioning material for use particularly in right-angled corner positions

in order that both the bottom of the abrasive material and the side or end portions can be used for sanding purposes, polishing, or the like, if desired. Likewise the face 19 of the base member 10 is slightly larger and extends beyond the sides and ends of the top portions 15, 16, 17 and 18 of the base member 10, so that the tool can be placed in abrading position without being close enough to the work-piece to injure the hands of the operator while the device is in use.

In operation the device will be easily understood in that when it is desired to set the tool up for work the plate 24 and cushioning member can be removed without the use of tools by being pulled away from the magnets 26, 26 a sufficient distance so the plate is outside of the magnetic field of the magnets 26, 26 and a strip of abrasive placed around the cushion 32 and the plate 29, with the ends folded inwardly over the top of the plate 29 and the plate 29 put into position adjacent the face 19 of the holding block 10 while this material is being held in the fingers of the operator, with the dowel pins 30 and 31 being in register with the bores 27 and 28, and as the plate 29 thus held is brought into position so that the dowel pins are about to enter the openings, the metal plate is within the magnetic field of the magnets 26, 26 so that the plate with the abrasive therearound is drawn against the face 19 of the base member 10 and held in position with sufficient strength so as not to be easily removed therefrom, and sufficient to hold the abrasive material in tight position around the cushion member 33 when the device is ready for use. The removal or replacement of the abrasive material is accomplished by the reverse operation by the workman grasping the top of the base member firmly in his hands and exerting an outward pull on the metallic member separating the metallic member from the magnets when the abrasive material 29 can be removed or replaced with another piece of abrasive material and different kind of material or a piece of polishing material as may be desired and thereupon replaced so that the edges are gripped between the base of the member 24 around its marginal edges and the face 19 of the base plate 10.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

What is claimed is:

1. An abrasive holder comprising in combination a non-magnetic base member, a magnet mounted thereon on one face thereof and a metallic abrasive holder of substantially the same dimensional area as the face of the base member fitted against the said magnet.

2. An abrasive holder comprising in combination a non-magnetic base member having a magnet receiving recess in one face thereof, a magnet mounted therein and a metallic abrasive holder of substantially the same dimensional area as the face of the base member fitted against the said magnet.

3. An abrasive holder comprising in combination a non-magnetic base member, a pair of magnets mounted thereon in spaced relation with each other and a thin metallic abrasive holder

adjacent the said magnets and within their magnetic field.

4. An abrasive tool comprising in combination a non-metallic base member having a plurality of spaced recesses therein, magnets mounted in each of said recesses, a metallic plate fitted to one face of the base member in which the said magnets are mounted and abrasive material in sheet form folded around the said metallic plate with the edges of the abrasive material being held between the said plate and the said base member.

5. An abrasive tool comprising in combination a non-metallic base member having a plurality of spaced recesses in one face thereof, the said recesses being spaced from each other and from the side edges and ends of the holder, magnets mounted in the said recesses, a metal plate adapted to engage the face of the base member having the magnets mounted therein and a flexible abrasive member folded around the metal plate and having its edges clamped between the metal plate and the face of the base member.

6. An abrasive tool comprising in combination a non-metallic base member having a plurality of spaced recesses in one face thereof, the said recesses being spaced from each other and from the side edges and ends of the holder, magnets mounted in the said recesses, a metal plate adapted to engage the face of the base member having the magnets mounted therein, a flexible abrasive member folded around the metal plate and having its edges clamped between the metal plate and the face of the base member and means on said metal plate in engagement with the base member whereby the said metal plate is held against torsional movement with respect to the said base member.

7. An abrasive tool comprising in combination a non-metallic base member having a plurality of spaced recesses in one face thereof, the said recesses being spaced from each other and from the side edges and ends of the holder and having a plurality of spaced bores therein, magnets mounted in the said recesses, a metal plate adapted to engage the face of the base member having the magnets mounted therein and a plurality of pins carried by the said plate extending into the bores in the base member, a flexible abrasive member folded around the metal plate and having its edges clamped between the metal plate and the face of the base member.

8. An abrasive tool comprising in combination a non-metallic base member having a plurality of spaced recesses in one face thereof, the said recesses being spaced from each other and from the side edges and ends of the holder and having a plurality of spaced bores therein, magnets mounted in the said recesses, a metal plate adapted to engage the face of the base member having the magnets mounted therein and a plurality of pins fixedly mounted in the said plate extending into the bores in the base member, a flexible abrasive member folded around the metal plate and having its edges clamped between the metal plate and the face of the base member.
